UNITED STATES PATENT OFFICE.

VINCENT F. SLEZAK, OF CHICAGO, ILLINOIS.

DESIGN FOR A CASING FOR A WEIGHT-PRINTING MACHINE.

Application filed October 25, 1926. Serial No. 19,481. Term of patent 14 years.

To all whom it may concern:

Be it known that I, VINCENT F. SLEZAK, a citizen of Czechoslovakia, residing at Chicago, in the county of Cook, State of Illinois, have invented a new, original, and ornamental Design for Casing for a Weight-Printing Machine, of which the following is a specification, reference being had to the accompanying drawing, forming a part thereof.

Figure 1 is a front view of a casing for a weight printing machine, showing my design.

Fig. 2 is a small diagrammatic side elevation of the casing for the sole purpose of illustrating the contour thereof.

I claim:

The ornamental design for a casing for a weight printing machine, substantially as shown.

In testimony whereof, I affix my signature.

VINCENT F. SLEZAK.
